US0D1103628S

(12) United States Design Patent (10) Patent No.: US D1,103,628 S
(45) Date of Patent:  Dec. 2, 2025

(54) NON-WOVEN FABRIC FOR PANTS,
CLOTHING AND DIAPERS

(71) Applicant: Hetaida Technology Co., Ltd.,
Dongguan (CN)

(72) Inventor: Zhenguang Chen, Dongguan (CN)

(73) Assignee: HETAIDA TECHNOLOGY CO., LTD., Dongguan (CN)

() Term: 15 Years

(21) Appl. No.: 29/941,299

(22) Filed: May 9, 2024

(51) LOC (15) Cl. 05-05

(52) U.S. Cl.

USPC D5/60; D5/52
